UNITED STATES PATENT OFFICE.

SWEN BERGLING AND KARL ANDERSON, OF CHICAGO, ILLINOIS, ASSIGNEES TO RELIABLE HOIST COMPANY, OF CHICAGO, ILLINOIS, A CORPORATION.

HOIST.

Application filed September 21, 1925. Serial No. 57,517.

Our invention relates to improvements in hoists especially adapted for use in building operations or the like, the object of the invention being to provide simple, durable and efficient apparatus of this character, the present invention being an improvement over that disclosed in our pending application filed June 15, 1925, Serial No. 37,049.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side view of a portion of a hoisting apparatus embodying the invention,

Fig. 2 is a top plan view of the same,

Fig. 3 is a horizontal section of the same,

Fig. 4 is a vertical transverse section of the same,

Fig. 5 is a vertical longitudinal section of the same, and

Fig. 6 is a detail view illustrating brake actuating mechanism employed in the construction.

The preferred form of construction as illustrated in the drawings comprises a suitable frame 10 having a gear casing 11 mounted thereon. Arranged in the gear casing 11 are two axially aligning winding shafts 12 and 13, the shaft 12 carrying a winding drum 14 and the shaft 13 carrying a winding drum 15. As will be noted the two shafts 12 and 13 are mounted in suitable bearings formed in the sides of casing 11 and the winding drums 14 and 15 are mounted on said shafts outside of said casing. A hoisting cable 16 is partially wound upon the drums 14 and 15, said cable being passed over guide pulleys 17 between said drums so as to permit of the free travel of said hoisting cable from one drum to the other. As will be noted, the hoisting cable 16 is wound on each of the drums 14 and 15 in the same direction so that rotation of either of said drums in the same direction will cause winding up of the cable thereon, providing, of course, that at the same time the other drum is simultaneously released for unwinding.

As best shown in Fig. 3, the shafts 12 and 13 carry driving gears 18 meshing with

pinions 19 fixed to a driving shaft 20 in the gear casing 11. A clutch member 21 is splined on the shaft 20 between the pinions 19 and said pinions are provided on their inner faces with clutch teeth 22 arranged to engage the clutch 21. The clutch 21 is operatively connected with rocker arms 23 carried by a vertical shaft 24 mounted in casing 11 and extending through the top thereof. As best shown in Figs. 1 and 2, the shaft 24 carries at its upper end a rocker arm 25 connected by a link 26 with a rocker arm 27 on a vertical rocker shaft 28 mounted at the forward end of the casing 11. The rocker shaft 28 carries a cross arm 29 the ends of which are connected with the ends of a control cable 30, said control cable being the usual control cable employed for this purpose and whereby the rocker shaft 28 may be rocked either manually or automatically in the usual way.

It will be noted that the operation of the rocker shaft 28 will in turn operate the rocker shaft 24 and thus move the clutch 21 into or out of engagement with the clutch members 22 and thereby operate the gears 18 to drive one or the other of the shafts 12 or 13 and to release the other.

As best shown in Figs. 5 and 6 the rocker shaft 28 carries a rocker arm 31 on which is secured a double acting cam head 32 which is in substantially inverted V-form and normally engages a corresponding recess in a cam block 33 mounted on rocker arms 34 secured to a transverse rocker shaft 35. The rocker shaft 35 carries at its opposite ends rocker arms 36 connected by links 37 with brake bands 38 engaging brake drums 39 on the winding drums 14 and 15. By this arrangement as the rocker shaft 28 shifts in either direction from its normal central position, the cam head 32 operating on the cam block 33 raises the rocker arms 34 to rock the rocker shaft 35 upwardly, thus simultaneously applying the brake bands 38 to the brake drums 39. Each of the brake bands 38 is anchored by a link 40 to a corresponding post or abutment 41 on the frame 10 and the rocker shaft 35 is provided with a depending rocker arm 42 connected with a tension spring 43 adjustably secured by a rod 44 to a post or abutment 45 on the frame 10. By this arrangement it will be observed that the brake bands 38 will be normally held in operative engage-

ment with the brake drums 39 by the spring 43 but that upon rocking of the shaft 28 in either direction said brake bands will be released, thus freeing the corresponding winding drums.

As best shown in Figs. 3 and 5, the driving shaft 20 carries a driving gear 46 meshing with a pinion 47 on a shaft 48 carrying a driving gear 49 on the outside of the casing 11. Driving gear 49 meshes with a driving pinion 50 on the motor shaft 51 of electric motor 52. The motor 52 is operated to keep the driving gear 46 and the shaft 20 constantly rotating in the same direction but at relatively slower speed. It will be noted that by manipulating the cable 30 to rock the shaft 28 in either direction, the corresponding drum 14 or 15, as the case may be, will be operated to wind or retract the corresponding end of the hoisting cable 16 and pay out the other end thereof, and that when said rocker shaft is shifted back to normal position the operation of both drums will cease and the corresponding brake bands will be automatically applied to stop the movement of the hoisting cable.

The hoisting cable 16 is passed over suitable guide pulleys and connected with the usual elevator cages operating in the usual elevator shafts in the usual way, and if desired, the said elevator cages are arranged to automatically operate the control cable 30 as will be readily understood by those skilled in this art and is more fully disclosed in our co-pending application.

The construction disclosed is a simple and efficient hoisting apparatus especially adapted for use in building operations and the like. The specific form and arrangement of parts will be found to be an effective one for the purpose and one capable of economical manufacture and operation.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having described our invention, what we claim as new and desire to secure by Letters Patent is:

1. A hoist comprising a gear casing; two shafts mounted in said casing, said casing being provided with bearings in its sides and said shafts extending through said bearings and projecting from said casing; winding drums on said shafts outside of said casing; a hoisting cable extending between and wound upon said drums; gearing and clutch mechanism within said casing for operating said winding drums; and a driving

shaft within said casing and cooperating with said gearing and clutch mechanism for operating said winding shafts, substantially as described.

2. A hoist comprising a gear casing; two axially aligning winding shafts mounted in said casing, there being bearings for said shafts in the sides of said casing and said shafts extending through said bearings and projecting from the sides of said casing; winding drums on said shafts outside of said casing; a driven shaft extending through the side of said casing; gears and clutch mechanism located within said casing and connecting said driven with said winding shafts; means connected with said clutch mechanism and extending through a wall of said casing for operating said clutch mechanism; and a hoisting cable extending between and partially wound on said drums, substantially as described.

3. A hoist comprising a gear casing; two axially aligning winding shafts mounted in said casing and extending through the sides thereof; winding drums on said shafts outside of said casing; driving gears on said shafts within said casing; a driven shaft within said casing and carrying gears meshing with said winding shaft gears; a clutch mechanism on said driven shaft for operating said winding shafts; a rocker shaft in said casing and projecting through a wall thereof and operatively connected with said clutch mechanism; and a hoisting cable extending between and partially wound upon said drums, substantially as described.

4. A hoist comprising two axially aligning winding shafts; winding drums on said shafts; guide pulleys between said drums; a hoisting cable partially wound on said drums and extending over said guide pulleys; a driving gear on each of said winding shafts; a driving shaft adjacent said winding shafts; driving pinions on said driving shaft meshing with the driving gears on said winding shafts; clutch elements on the inner sides of each of said driving pinions; a clutch member splined on said driving shaft between said driving pinions and arranged to be shifted into and out of engagement with the clutch elements thereon; an electric motor; a reducing gear connection between said electric motor and said driving shaft; a rocker shaft arranged adjacent said shiftable clutch member and operatively connected therewith; a second rocker shaft operatively connected with said first rocker shaft; a cross arm secured to said second rocker shaft; an operating cable secured to the ends of said cross arm; a rocker arm on said second rocker shaft; a V-shaped cam head on said last mentioned rocker arm; a cam block having a cam recess fitting said cam head; a rocker arm secured to said cam block and to a brake rocker shaft; a brake

120
125
130

drum secured to each of said winding drums; ranged to hold said brake bands normally a brake band for each of said brake drums; substantially 10 an operative connection between each of as described.

5 said brake bands and said brake shaft, whereby operation of said brake shaft releases both of said brakes; a rocker arm ~~on~~ on said brake shaft; and a spring connected with said brake shaft rocker arm and ar-

In testimony whereof we have signed our names to this specification.

SWEN BERGLING.
KARL ANDERSON.
